UNITED STATES PATENT OFFICE.

WILLIAM H. HOYT, OF STAMFORD, CONNECTICUT.

DESIGN FOR A FIRE-SCREEN.

SPECIFICATION forming part of Design No. 14,338, dated October 2, 1883.

Application filed August 3, 1883. Term of patent 3½ years.

To all whom it may concern:

Be it known that I, WILLIAM H. HOYT, a citizen of the United States, residing at Stamford, in the county of Fairfield and State of Connecticut, have invented and produced a new and original Design for Fire-Screens, of which the following is a specification, reference being had to the accompanying drawings, forming part thereof.

10 Figure 1 is a front elevation of my newly-designed fire-screen, and Fig. 2 is an edge thereof.

The leading feature of my design consists in a night scene formed upon the screen, combined with a bird shown in outline or relief.

15 A represents the dark body or background of the screen, arranged in a frame supported as shown in the drawings, and B represents the bird. The body A is made of black cloth, and the bird B is shown in relief, being a 20 stuffed night-heron, secured to the body or background A. On the dark body or background A is shown a night scene consisting of the moon b and water c, showing reflection of the moon. In the water are shown water-plants d, and at the front, at the lower part of the screen, is shown the spot e of shore or ground, and the bird B is so arranged on the screen, with reference to this spot of ground, as to appear to stand upon it. A little beyond the bird B is shown growing the marsh-plants f, the whole presenting to the eye the effect of a lonely night scene in summer on the bank of a river or like.

25 I claim—

A design for a fire-screen, consisting of the dark background A, the bird B, the moon b, the water c, the ground spot e, and the marsh-plants f, the whole representing a summer night scene, as shown and described.
